UNITED STATES PATENT OFFICE.

WILLIAM H. COLE, OF WALTHAM, MASSACHUSETTS.

SYSTEM OF ELECTRICAL DISTRIBUTION.

1,276,331.

Specification of Letters Patent. Patented Aug. 20, 1918.

Application filed August 12, 1915, Serial No. 45,233. Renewed December 8, 1917. Serial No. 208,327.

To all whom it may concern:

Be it known that I, WILLIAM H. COLE, a citizen of the United States, residing at Waltham, county of Middlesex, State of Massachusetts, have invented an Improvement in Systems of Electrical Distribution, of which the following description, in connection with the accompanying drawing, is a specification, like characters on the drawing representing like parts.

This invention relates to systems of electrical distribution and particularly to those systems which employ a plurality of conductors arranged in parallel and extending between two receiving or distributing stations. In my patent No. 1,152,880, dated September 7, 1915, I have illustrated and described an electrical-distributing system of this type having means for automatically isolating from the system any conductor when it becomes faulty.

The device of the above-mentioned patent is designed to become operative to disconnect a conductor from the system when the value of the current carried by said conductor differs from that of another conductor by a predetermined amount. This predetermined amount of normal unbalance is provided for by proper adjustment of the relays and balancing transformers, and in actual practice, therefore, said relays and balancing transformers are adjusted so as to permit the maximum amount of normal unbalance to occur without operating the connecting devices, but to become operative to cause disconnection whenever faults occur which result in unbalanced currents greater than the amount occurring when no faults are present in the protected conductors. The greater the amount of expected unbalance during working conditions, the coarser must be the setting of the relay and the coarser the relays are set the less efficient will the apparatus be in giving protection.

In the usual lay-out of an electrical-distributing system having parallel feeders, it frequently happens that the relative carrying capacity of the parallel-connected feeders will vary materially due to such causes as unequal length, difference in cross section, difference in reactance, different temperatures, etc. Again, it may be desirable to take off energy from one or more of the

parallel-connected conductors at points between the terminals thereof. It is, therefore, desirable to provide a construction which while capable of sensitive discrimination in the case of fault currents, is not responsive to the known or predetermined normal unbalance or difference in current values which may exist during normal working of the system.

The object of my present invention is to provide means to be used in connection with two or more parallel-connected conductors subject to power flow in either direction and which may for one cause or another normally carry currents of values which vary in ratio with respect to the current in one or more of the other conductors in the same parallel group, which means will remain inoperative so long as said ratio remains within predetermined limits, but which becomes operative to cut out and isolate any conductor in the group whenever the current therein becomes such as to have a value greater than the maximum or smaller than the minimum value permitted by the predetermined ratio of maximum to minimum current values in the parallel conductors. With an apparatus embodying my present invention, therefore, it is possible to carry normally a greater or less current in one conductor than in another parallel conductor, and yet to cut out a faulted conductor whenever a fault develops which causes the ratio between the maximum and minimum current values in the several conductors to exceed a predetermined limit.

In the following description a current of a conductor having a reverse direction of flow with respect to the currents in the other conductors is to be considered as having a minimum value as compared with the maximum current in the normal direction equal to its algebraic difference from said maximum current.

I accomplish the above objects by employing one or more relays associated with the conductors and which become operative only when the current in one of the conductors is less than or exceeds the current in another conductor by a predetermined percentage.

In order to give a proper understanding of the invention, I have illustrated herein some selected embodiments thereof which

will now be described, it being understood that the invention is not limited to the construction shown.

Figure 1 is a partially diagrammatic view showing one embodiment of my invention;

Figs. 2, 3, 4, 5 and 6 are similar views showing different embodiments of my invention;

Fig. 7 is a diagrammatic view showing my invention as applied to three or more parallel-connected conductors.

Referring first to Fig. 1, which shows a simple embodiment of the invention, 1 and 2 designate the mains or two receiving or distributing stations, and these mains may be either in a ring, tandem or radial system of distribution. 3 and 4 indicate two conductor members or feeders connecting said mains, said feeders being arranged in parallel. Each conductor or feeder is shown as provided at each end with a cut-out switch 5 by which it may be disconnected from the system, and I have shown each switch as controlled or actuated by a trip coil 6 that is in a circuit 7 containing a battery 8 or other source of electrical energy. The two trip coils 6 at each end of the conductors 3 and 4 are shown in the same circuit 7 so that when this circuit is energized, both trip coils therein are energized and both conductors are thereby disconnected from said end of the system. The parallel feeders or conductors 3 and 4 may carry currents of different values for any one of the various reasons above suggested, that is, the current in the conductor 3 may under normal working conditions differ considerably from that in the conductor 4. This current difference is commonly described as the "differential current." My invention, as stated above, comprises means for disconnecting said conductors from the system, which means is non-operative so long as the ratio between the current values in the conductors 3 and 4 is within a predetermined limit, but which becomes operative whenever such ratio exceeds such predetermined limit. The conductors 3 and 4 are, therefore, permitted to carry currents of different values uninterrupted so long as the ratio between the current values is within a predetermined amount, but when the ratio exceeds or goes beyond this predetermined amount, then the device becomes operative to disconnect the conductors from the system.

The circuit 7 is normally open at the contacts 9, and means are employed for closing this circuit when the ratio between the current values carried by the conductors 3 and 4 exceeds a predetermined limit, which means is non-operative to close the circuit so long as said ratio is within a predetermined limit. The device shown in Fig. 1 for this purpose comprises two elements, each carrying two windings, one element being relatively

fixed and the other element being relatively movable. Each element is wound with two coils, the relative number of turns in the coils being chosen with regard to the percentage of unbalance it is desired to permit the parallel conductors to operate under. The two elements of the relay comprise the relatively-fixed element 10 and the relatively-movable element 11, which is shown as pivotally mounted at 22. This fixed element 10 is wound with the two coils 12 and 13, and the relatively-movable element 11 is wound with the two coils 14 and 15.

The winding 12 on the element 10 and the winding 14 on the element 11 are connected in series in a circuit 16 which has therein the secondary 17 of a transformer, the primary 18 of which is in the conductor 3. Similarly, the winding 13 of the element 10 and the winding 15 on the element 11 are in series in a circuit 19 which has therein the secondary 20 of a transformer, the primary 21 of which is in the conductor 4. With this arrangement, the current carried by the conductors 3 and 4 will induce currents in the circuits 16 and 19, thus energizing the elements 10 and 11. These windings 12, 13, 14 and 15 are so arranged that under normal current conditions one of the windings of each element will predominate over the other, thus determining the polarity of said elements and the direction in which the movable element 11 tends to turn. In the construction shown in Fig. 1, the winding 13 predominates over the winding 12, and the winding 14 predominates over the winding 15, and as a result under normal conditions the element 11 which is pivoted at 22 will tend to move counter-clockwise. This element 11 carries a contact 23 which is normally held against a stop 24 by the arrangement above described, but which is adapted to close the contacts 9 when said element moves away from the stop. The arrangement of these windings is such that so long as the ratio between the current values in the conductors 3 and 4 remains within a predetermined limit, the contact 23 will be held against the stop 24, but if abnormal conditions arise which result in a sufficient increase or decrease in the current in one conductor relative to that in the other to carry the ratio between the currents beyond the predetermined amount, the heretofore predominating winding of one element only ceases to predominate, and its companion winding becomes predominative whereby the polarity of said element is reversed, thus causing the movable element 10 to move clockwise and close the circuit 7 at the contacts 9. This results in operating the trip coils 6 and opening the feeders at 5.

As illustrating the operation it may be assumed that the two windings on each element are in a ratio of four to three, in which

case the conductors 3 and 4 would be permitted to carry current values varying from each other by the ratio three to four before the relay has any tendency to operate. If, 5 however, the current in the conductor 4, for instance, should increase relative to that in the conductor 3 so that the ratio between the current values in the two conductors was greater than three to four, such increased 10 current will cause the winding 15 to predominate over the winding 14, thus reversing the polarity of the element 11 and causing the relay to operate. In case the relative increase in current should be in the conductor 15 3, then when the relative current values exceed a predetermined ratio, the winding 12 will be caused to predominate over the winding 13, thus reversing the polarity of the element 10 and causing the 20 relay to operate similarly.

The de ice will, therefore, remain inactive so long as the ratio between the current values in the conductors 3 and 4 remains within the predetermined limit, regardless 25 of fluctuations in the current carried by said conductors, but as soon as the relative values of the currents in the two conductors vary to such an extent that the ratio of said values exceeds the predetermined limit for 30 which the relay is designed, then said relay becomes operative to cut the conductors from the system.

In Fig. 2 I have shown a different embodiment of my invention operating on the same principle, however. In this embodiment of the invention the relay for closing the circuit 7 comprises the two cores 32 and 33 connected to the pivoted yoke 31 to which the contact 23 is rigidly secured. The secondary 20 of the transformer in the conductor 4 is connected to a circuit 34 which has therein a winding 35 for the core 32 and another winding 36 for the core 33. The secondary 17 of the transformer associated with the conductor 3 is in a circuit 37 having therein one winding 38 for the core 32 and another winding 39 for the core 33. The windings 35, 38 for the core 32 are arranged to augment each other under 45 normal current conditions, while the windings 39 and 36 for the core 33 are arranged to oppose each other under normal current conditions. As a result the core 32 is subject to the combined action of the coils 35 50 and 38, while the core 33 is acted upon by the difference in effect between the windings 36 and 39. Said windings 36 and 39 are relatively fine windings, while the other windings are relatively coarse windings, and 55 the ratio between the fine and coarse windings is chosen with relation to the predetermined ratio between the current values permitted to exist in the conductors 3 and 4. If abnormal conditions arise by which the 60 ratio between the current values in the con-

ductors 3 and 4 varies beyond the predetermined amount, one of the windings 36, 39 will predominate over the other sufficiently to overcome the effect of the windings 35, 38 on the core 32, thus turning the yoke 31 and causing the contact 23 to close the circuit 7, with the result that the conductors will be cut out from the circuit. 70

In Fig. 3 I have shown another embodiment of my invention which has a relay comprising a fixed and movable element 10 and 11, as shown in Fig. 1. In this embodiment, however, each element has a single winding thereon, the element 10 having a winding 42 in a circuit 43 including the secondary 17 associated with the conductor 3 and the element 11 having a winding 44 thereon in a circuit 45 having therein the secondary 20 associated with the conductor 4. The effect of the windings 42 and 44 is to hold the element 11 against the stop 40 under normal conditions of current flow in conductors 3 and 4. This element 11 has rigid therewith an arm 46 which is connected by a link 47 with the movable core 48 in a coil or solenoid having two opposed windings 49 and 50 thereon, one of the windings being in a circuit 43 and the other in the circuit 45. These windings 49 and 50 are so designed that so long as the ratio between the current values in the conductors 3 and 4 is within the predetermined limit, the resultant effect of the windings on the core 48 is insufficient to overcome the action of the windings 42 and 44. When, however, the ratio between the current values in the conductors 3 and 4 exceeds the predetermined ratio then the windings 49 and 50 predominate over or assist the action of the other windings, thus turning the element 11 95 and closing the circuit 7 at the contacts 9, thereby cutting the conductors from the circuit. 90

In Fig. 4 I have shown an embodiment of my invention similar to that shown in Fig. 2 in that the contact 23 for closing the circuit 7 is carried by a pivoted yoke 31 to which is attached the two cores 52 and 53. The core 53 has a coarse winding 54 thereon which is in a circuit 550 that includes both of the secondaries 20 and 17 associated with the conductors 4 and 3, said winding being placed in said circuit midway electrically between the secondaries 17 and 20. The core 52 has a fine winding 55 theron which is 110 connected to the central portion of the winding 54 and to one side of the circuit 550 at a point midway electrically between the secondaries 17 and 20. With this arrangement the core 53 will be subject to the combined action of the current induced by both 115 transform., while the winding 55 will be subject to the action of the difference of said currents. The coil 54 will predominate 120 under normal conditions and thus hold the 125 coil 55. 130

contact 23 against the stop 40. When the ratio between the currents carried by the conductors 3 and 4 varies to such an extent that the fine winding 55 will predominate over the winding 54, then the contact 23 will be actuated to close the circuit 7.

In Fig. 5 I have shown another embodiment of my invention which is similar to that shown in Fig. 3 except that in the place of the differential coil 49, 50 of Fig. 3, I use a choke coil having two windings, one in each of the circuits 43 and 45. These windings are so constructed that if when the currents in the conductors 3 and 4 are in the same direction the ratio between the currents in said conductors increases beyond the predetermined amount, then one of the windings will predominate over the other sufficiently to reverse the current in the latter winding and thus reverse the polarity of one of the elements of the relay. In case the ratio between the currents in the conductors 3 and 4 increases beyond the predetermined amount, due to a reversal of current flow in one conductor relative to that in the other, then the polarity of one of the elements 10 and 11 is reversed without the assistance of the choke coil, which in such case becomes negligible in its effect on the operation of the relay. The choke coil is herein shown as a core element 61 having the two windings 62 and 63 thereon, the winding 62 being in the circuit 45 which includes the winding 44 of the relatively-movable element 11 of the relay, and the winding 63 of the choke coil being in the circuit 43 which includes the winding 42 of the relatively-fixed element 10 of the relay. The two windings 62, 63 under unbalanced current conditions coöperate as a transformer and are arranged so that each winding induces in the other winding a current opposed to that normally existing therein. With this construction it will be seen that if whenever the currents in the conductors are in the same direction and the current in either of the conductors increases relative to that in the other to such an extent as to carry the ratio between the currents outside the predetermined limit, then one of the coils 62, 63 will predominate over the other coil sufficiently to reverse the direction of current in the circuit of said other coil and thus reverse the polarity of one element of the relay. When reversal of polarity of one element of the relay occurs, due to either the coöperation of the choke coil or to the reversal of current in one of the conductors, relative to that in the other, the circuit 7 will be closed by the relay and the conductors will be disconnected from the system.

In Fig. 6 I have shown an apparatus somewhat similar to Fig. 4 except that the connections are such that the coarse wind-

ing 54 is connected to the central portion 65 of the fine winding 55. In this embodiment the action of the winding or coil 54 on its core 53 is that due to the combined currents developed in the transformers associated with both conductors 3 and 4, while the action of the winding or coil 55 on its core 52 is the result of the difference of the currents. So long as the ratio between the current values in the conductors 3 and 4 remains within the predetermined limit, the coil 54, 75 will predominate, thus holding the circuit 7 open, but if this ratio increases beyond a certain amount, the coil 55 will predominate thus closing the circuit.

All of the above embodiments of my invention are illustrated as applied to a pair of parallel feeders only. My invention is also applicable where more than two parallel feeders are employed, and in Fig. 7 I have illustrated such an embodiment of my invention. In this arrangement the relays for the various conductors or feeders are electrically connected with each other and the coöperation of two relays is necessary to close the tripping circuit for the trip coil 90 of any conductor. In Fig. 7 1 indicates the main and a, b, c indicate three parallel feeders. A switch 5 is provided for connecting each feeder to the main 1, each switch being controlled by a trip coil 6. A, 95 B and C indicate the relays, these relays being shown of the type illustrated in Fig. 1, that is, each comprising a relatively-stationary element 10 and the relatively-movable element 11 pivotally mounted at 22 and 100 carrying the contact member 23.

Each stationary element 10 is provided with two windings 120, 130, and each movable element is provided with two windings 140, 150. The windings 130, 120 and also 105 the windings 140, 150 are normally opposed to each other and the number of turns in each winding is chosen with relation to the percentage of unbalance it is desired to permit between the current in any conductor 110 and that of any other conductor. The winding 120 of each relay is not only connected in series with the winding 140 of the same relay and the secondary 170 of the transformer in the adjacent conductor, but is also 115 connected in series with the windings 130 and 150 of the next adjacent relay. The circuit 70 of each trip coil 6 is provided with two pairs of contacts, one pair 90 being closed by the contact element 23 of one relay and the other pair 91 being closed by the contact 23 of the next adjacent relay with which the first-named relay is electrically connected. It will, of course, be understood that the circuit connections w, x, y, z at the left Fig. 7 are connected to the corresponding circuit connections on the right.

With the above arrangement the relays

will be held in the position shown in Fig. 7 with the contacts 23 against the stops 24 so long as the ratio of current unbalance in the various conductors in which the relays 5 are wound is not exceeded. If, however, the current in any one of the conductors, such, for instance, as the conductor *b*, increases for any reason to such an extent that the ratio between said current and that 10 in the other conductors exceeds the predetermined limit, then the relays B and C become operative thereby closing the contacts. The relay B will close the trip coil circuit 70 for the conductor *b* at 90, and the relay 15 C will close said circuit at 91, thus energizing the trip coil 6 and cutting the conductor *b* from the system. This operation disconnects the conductor *b* from the system.

In the embodiment of my invention 20 shown in Figs. 2, 4 and 6 it will be noted that each relay is influenced by both the sum and the difference of the currents in two conductors and that the construction is such that the effect on the relay of the sum 25 of the currents under normal working conditions predominates over the effect thereon of the difference between the currents, so that the relay will normally be retained in its inoperative position. When, however, 30 abnormal current conditions arise which produce a difference between the currents in said conductors which is greater than a predetermined percentage of the current in either conductor, then the effect on the relay 35 of the difference between said currents predominates over the effect on said relay of the sum of the currents, and the relay becomes operative to disconnect one or both of the conductors from the system.

40 I claim:

1. The combination with a plurality of parallel-connected conductors extending between two points in an electrical transmission or distribution system, of relays for 45 disconnecting said conductors from the system, and relay-controlling means which holds the relays inoperative so long as the ratio of the currents in the conductors of any associated pair of conductors remains within 50 a predetermined limit, but which renders said relays operative to disconnect said pair of conductors from the system whenever the ratio of the currents carried in the conductors of said pair exceeds a predetermined 55 limit due to an increase or a decrease or a reversal in direction of the current in either conductor of said pair relative to that in the other conductor.

2. The combination with two parallel- 60 connected conductors extending between a receiving and distributing station, of a cut-out at each end of each conductor, and operating means therefor which is held inoperative so long as the ratio between the cur-

rent carried in said conductors remains 65 within a predetermined limit, but which becomes operative whenever the ratio of the currents carried in the conductors exceeds a predetermined limit due to an increase or 70 a decrease or reversal of direction of the current in one conductor relative to that in the other.

3. The combination with a plurality of parallel-connected conductors extending between two points in an electrical transmission 75 or distribution system, of relays for disconnecting said conductors from the system, and means connecting said relays to the system whereby each relay is subject to the effect of both the sum and the difference 80 of the currents in two associated parallel conductors and under normal working conditions will be held inoperative by the preponderance of the effect of the sum of the currents over the effect of the difference, but 85 will become operative to disconnect the conductors from the system whenever the current in one of said conductors increases, decreases or reverses in direction relative to that in the other conductor thereby to produce 90 a current difference in said conductors which exceeds a predetermined percentage of the current in either conductor.

4. In a system of electrical transmission or distribution of that type having a plurality of parallel-connected conductors grouped in feeding sections and subject to power flow in either direction, the combination with disconnecting devices for disconnecting each of the conductors from the 100 system, of means to cause the disconnecting devices for any conductor to become operative to disconnect said conductor from the system only when the ratio between the value of the current therein and the value 105 of the current in an associated conductor exceeds a predetermined limit due to a fault involving the first-named conductor.

5. In a system of electrical transmission or distribution of that type having a plurality of parallel-connected conductors grouped in feeding sections and subject to power flow in either direction, the combination with disconnecting devices for disconnecting each of the conductors from the 110 system, of means for actuating the disconnecting devices, which means are inoperative so long as the ratio between the value of the current in any conductor and the value of 115 the current in an associated conductor remains within a predetermined limit, but which becomes operative when said ratio exceeds said limit due to a fault involving either of said conductors.

6. In a system of electrical transmission 120 or distribution of that type having a plurality of parallel-connected conductors grouped in feeding sections and subject to

power flow in either direction, the combination with disconnecting devices for disconnecting each of the conductors from the system, of means to cause the disconnecting device for any conductor to operate thereby to disconnect said conductor from the system whenever the current therein has a value

greater than the maximum or smaller than the minimum value permitted by a predetermined ratio of maximum to minimum current value in the parallel conductors.

In testimony whereof, I have signed my name to this specification.

WILLIAM H. COLE.
